J. C. GROETSCH & C. L. SAAL, JR.
APPARATUS FOR DELIVERING MAIL BAGS FROM RAILWAY TRAINS.
APPLICATION FILED DEC. 4, 1907.

902,228.

Patented Oct. 27, 1908.

UNITED STATES PATENT OFFICE.

JACOB CHRISTIAN GROETSCH AND CHRISTIAN LUDWIG SAAL, JR., OF PATERSON,
NEW JERSEY.

APPARATUS FOR DELIVERING MAIL-BAGS FROM RAILWAY-TRAINS.

No. 902,228.

Specification of Letters Patent. Patented Oct. 27, 1908.

Application filed December 4, 1907. Serial No. 405,002.

To all whom it may concern:

Be it known that we, JACOB CHRISTIAN GROETSCH and CHRISTIAN LUDWIG SAAL, Jr., citizens of the United States, residing in Paterson, Passaic county, New Jersey, have invented a certain new and useful Improvement in Apparatus for Delivering Mail-Bags from Railway-Trains; and we do hereby declare the following to be a full, clear, and exact description of the invention, such as will enable others skilled in the art to which it appertains to make and use the same, reference being had to the accompanying drawings, and to letters of reference marked thereon, which form a part of this specification.

Our invention has for its object to provide a mechanism whereby mail bags may be discharged from moving trains without opportunity for the bag or its contents to be injured in any manner while the transfer is taking place, which mechanism shall be simple and inexpensive in construction, reliable in operation, and capable of being handled without danger to the operator.

Our invention consists in providing, parallel with the railway, an inclined runway whose higher end is in the direction of progress of passing trains, in combination with a hook-shaped holder for the mail bag, and a suitable arm carried by a car or other vehicle which, being adapted to hold the hook, carrying the mail bag, in a vertical plane occupied by the runway, will permit the hook to disengage itself therefrom as soon as it is securely deposited on the runway.

Our invention will be found fully illustrated in the accompanying drawing, 40 wherein,

Figure 1 is a view of our invention in side elevation, only a part of a car being shown; Fig. 2 is a view partly in rear elevation and partly in transverse section through the car door; Fig. 3 is a rear view of the hook-shaped holder for the mail bag; Fig. 4 is a side view of what is shown in Fig. 3; and, Fig. 5 shows the pivotal support for the hook-shaped holder.

In said drawing, *a* designates a railway and *b* a car.

At the side of the railway may be arranged two posts *c*, *d*, the former being shorter than the latter and being the first reached by a train in passing them. Be-

tween these two posts is stretched a taut inclined wire *e* whose lower end, of course, is secured to the shorter post *d*. This form of inclined runway is probably the most practical one because it is not only simple 60 and inexpensive in construction but adequately serves the purpose in hand.

f designates the mail bag or pouch, the same having the usual rings *g* at the top and bottom thereof. In accordance with 65 our invention, a holder *h* for the temporary support of the mail bag is provided. This may be a heavy-wire bent to form the hook *i* at its upper end and the smaller hook *j* at its lower end, the latter being adapted to 70 receive one of the rings *g* of the mail bag and preferably having a spring-guard *k* which may be riveted to the shank *l* of the holder *h*. Preferably, an eye *m* is formed in the shank of the holder near its upper end 75 by twisting or forming a coil in the wire thereof. The end of the hook *i* is also bent back on itself, its extremity *n* standing free of the remainder of the hook *i*, and coöperating with this rebent portion is a spring- 80 guard *o* riveted to the shank *l* of the holder, said spring-guard being adapted to lightly bear against the extremity *n* of hook *i*. It will be understood, however, that we are not necessarily limited to the details of construction just set forth.

The support for the holder *h* is in the form of a bar *p* pivoted at *q* in the side of the car door, the same preferably having an arm *r* which extends laterally of the bar and rearwardly with reference to the car, being inclined upwardly as best shown in Fig. 4. The bar *p*, which is pivoted between its ends, may carry a weight *s* on its inner end, which, as soon as the weight of the mail bag is relieved from its free or outer end, causes the bar to automatically swing into the upright position, out of the way.

In the operation of the mechanism, the holder *h* is first hooked into one of the rings 100 of the mail bag and then arranged on the bar *p* with its inclined arm *r* penetrating the eye *m* of the holder. The eye should have sufficient diameter so that under the weight of the holder and the mail bag it will lie 105 squarely against the side of the bar *p* so that the plane of the hook is kept substantially at right angles to the longitudinal axis of the car. The holder being supported on the arm *r* of bar *p*, the latter is allowed to 110

swing down into the position shown in Fig. 2, where the arm is sustained by a stop *t* on the car door in substantially a horizontal position. This brings the hook *i* in the vertical plane of the runway *e*, so that when the car passes the runway the wire *e* will force its way between the extremity *n* of the hook and the spring-guard *o* and bear against the inside of the hook as is shown in dotted outline in Fig. 3. The momentum of the parts will carry the bag up the runway until the incline of the latter overcomes such momentum, by which time the holder will have slipped off the arm *r* of bar *p*, thus transferring the holder and the bag from the car to the runway. The holder will then slide back down the runway in convenient reach for its removal therefrom, while the bar *p* will automatically assume its vertical position under the action of its weight *s*. It will be understood that the purpose of the spring guard *o* and coöperating extremity *n* of hook *i* is to insure against the holder jumping from the runway on its first impact therewith.

Having thus fully described our invention, what we claim and desire to secure by Letters Patent of the United States is—

1. The combination, with a railway and a vehicle running thereon, of an inclined runway arranged substantially parallel with the railway, a hook-shaped bag-holder, and means, comprising a rearwardly extending arm, for removably supporting said bag-holder on the vehicle in position to be engaged by said runway, substantially as described.

2. The combination, with a railway and a vehicle running thereon, of an inclined runway arranged substantially parallel with the railway, a hook-shaped bag-holder, and means, comprising a rearwardly extending upwardly inclined arm, for removably sup-

porting said bag-holder on the vehicle in position to be engaged by said runway, substantially as described. 45

3. The combination, with a railway and a vehicle running thereon, of an inclined runway arranged substantially parallel with the railway, a hook-shaped bag-holder, and a support for the bag-holder pivoted in the vehicle on a horizontal axis and comprising a rearwardly extending arm adapted to receive the bag-holder, substantially as described. 50

4. The combination, with a railway and a vehicle running thereon, of an inclined runway arranged substantially parallel with the railway, a hook-shaped bag-holder, and a support for the bag-holder pivoted in the vehicle on a horizontal axis and comprising a rearwardly extending upwardly inclined arm adapted to receive the bag-holder, substantially as described. 55

5. The combination, with a vehicle, of an inclined runway, a hook-shaped bag-holder, and a support for the bag-holder pivoted in the vehicle on a horizontal axis and comprising a rearwardly extending upwardly inclined arm adapted to receive the bag-holder, substantially as described. 60

6. In combination, with a vehicle and an inclined runway, a bag-holder provided with an eye in its upper portion and having its ends hook-shaped and a support for the bag-holder having an arm adapted to be received by said eye, substantially as described. 75

In testimony, that we claim the foregoing, we have hereunto set our hands this 30th day of November, 1907.

JACOB CHRISTIAN GROETSCH.
CHRISTIAN LUDWIG SAAL, JR.
